UNITED STATES PATENT OFFICE.

WILLIAM YEAGER AND BROR E. WESTLIN, OF BROOKLYN, NEW YORK.

CLAMP.

SPECIFICATION forming part of Letters Patent No. 521,872, dated June 26, 1894.

Application filed October 30, 1893. Serial No. 439,462. (No model.)

To all whom it may concern:

Be it known that we, WILLIAM YEAGER and BROR E. WESTLIN, of Brooklyn, county of Kings, and State of New York, have invented 5 a new and useful Improvement in Clamps, of which the following is a specification.

Figure 1 is a plan view of the clamp. Fig. 2 is a side view and Fig. 3 an end view.
a d' are side plates. b is a stud secured 10 between them at one end. c is a sheave rev-
olubly mounted between them toward the other end. d d' are the jaws of a clamp mounted upon one of the plates a at the said other end; one of said jaws being arranged 15 to slide up and down in the guideways e e' and being operated by the thumb-screw j threaded to the cross member k at the top of said guideways. The cross member k, the guideways e e' and the lower jaw d' consti-
20 tute substantially a loop with one side of which the plate a joins. One end, as l, of a rope is placed around the stud b and secured there; another end, as l', is passed between the jaws d and d', thence around the sheave c and 25 thence back again on top of itself between the jaws. The thumb-screw j is then screwed down so as to clamp the end l'. Now, by un-
screwing so as to raise the jaw d, the end l' will be unclamped sufficiently so that by pull-
30 ing on its loose end, it can be pulled around the sheave c till taut. Thereupon, by screwing down the thumb screw j it will be grasped firmly by the jaws and held there. This con-

trivance, comprising the sheave c and the clamp, may be employed for only one end of 35 the rope; and we therefore do not wish to be limited to the stud b as the means to retain the clamp in the position desired.

The principal use of the sheave c is to aid the clamp in holding the rope securely and 40 to allow the rope to pass freely over it in increasing and decreasing the slack so as to facilitate placing the rope in a position to be secured by the clamp. Where a rope is understrain, as of a suspended weight, its length 45 may be taken up or increased without removing the strain. This feature makes it exceedingly valuable in many instances, as for example, in the case of a clothes line where the length of the line needs frequent chang- 50 ing so as to control the sag of the line under the weight of the clothes.

We claim—

1. A rope clamp having the pulley c and the clamping jaws d d' supported by a suitable frame, substantially as described. 55
2. In a rope clamp in combination, the stud b, the pulley c and the clamping jaws d d' and a suitable frame, substantially as described.

WILLIAM YEAGER.
BROR E. WESTLIN.
